(57) **CLAIM**

We claim the ornamental design for a illuminated vehicle grab handle with keypad, substantially as shown and described.

DESCRIPTION

FIG. 1 is a front perspective view of an illuminated vehicle grab handle with keypad showing our new design, the dashed lines represent curvatures in the mounting brackets;

FIG. 2 is a side elevational view thereof;

FIG. 3 is a side elevational view thereof;

FIG. 4 is an end elevational view thereof;

FIG. 5 is an end elevational view thereof; and,

FIG. 6 is a top plan view thereof, the undisclosed bottom is not part of the claimed design.

No claim is made to the bottom of the handle.
